UTILITY CHAIR FOR A HAIRDRESSER

Jeanette Morgan, 5867 Lotus,
St. Louis, Mo. 63112

Filed Sept. 30, 1974, Ser. No. 510,214

Term of patent 14 years

Int. Cl. D6—01

U.S. Cl. D6—22

FIG. 2

FIG. 1

FIG. 5

FIG. 4

FIG. 3

FIG. 1 is a perspective view of a utility chair for a hairdresser showing my design;
FIG. 2 is a top view thereof;
FIG. 3 is a front view thereof;
FIG. 4 is a side view thereof;
FIG. 5 is a rear view thereof.

I claim:
The ornamental design for a utility chair for a hairdresser, as shown.
